UNITED STATES PATENT OFFICE.

FENN H. PALMER AND SAMUEL C. CARTER, OF LOS ANGELES, CALIFORNIA, ASSIGNEES
TO JAMES R. PALMER, OF LOS ANGELES, CALIFORNIA.

AUTOMATIC SELF PLUMBING AND OILING PUMP-HEAD.

1,317,096.

Specification of Letters Patent. Patented Sept. 23, 1919.

Application filed February 2, 1916. Serial No. 75,853.

To all whom it may concern:

Be it known that we, FENN H. PALMER and SAMUEL C. CARTER, citizens of the United States, residing at Los Angeles, in 5 the county of Los Angeles and State of California, have invented an Automatic Self Plumbing and Oiling Pump-Head, of which the following is a specification.

This invention relates to pump-heads for 10 use in a propeller pump in which the propellers are mounted on a shaft that extends down into pump casing through which the water is impelled from a well or other source of supply. The shafts of such propeller pumps are rotated at high speed and 15 support the column of water being pumped.

It is very important and necessary that 20 the shaft of such a pump shall be perfectly plumb and that it shall be in perfect alignment with the pump casing, and that the supporting bearing therefor shall be perfectly level and shall be kept perfectly lubricated in order to prevent it from running hot.

25 An object of this invention is to so construct a pump-head that it will be automatically plumbed and the bearing will be held level, and the pump shaft will be automatically aligned with the pump casing by 30 the action of gravity irrespective of an un-level condition of the base.

That is to say, an object is to make provision whereby it is not important that the base of the pump head shall be level, and 35 whereby the bearing support or body of the pump head will be invariably brought to true position upon simply placing said body or support on the pump head base.

Further objects are to make provision 40 whereby the belt pull is borne by radial bearings; to make it easy to change the pulleys to meet various conditions; to allow easy removal of the belt; to leave the pump shaft free from all side strain making a full 45 floating drive-shaft; to make it impossible for water to enter the bearing through defective packing; and to avoid affecting the operation of the pump by a leak at the bearing.

50 An object of the invention is to make provision whereby the bearing of the propeller shaft is made to support the weight of the shaft and also the thrust of the belt upon

the pulley in the most efficient way and to provide a superior oiling device that is positive in its operation and that will conserve the oil, prevent its evaporation and loss by splashing or leakage and will also protect the bearing from dust and rust.

Other objects of the invention are simplicity, cheapness and compactness, and superior ease and convenience of installation and operation.

A further object of the invention is to provide a full floating shaft for propeller 65 pumps.

The accompanying drawing illustrates the invention.

Figure 1 is a vertical axial section centrally through the discharge bend.

Fig. 2 is a plan in section on line 2—2 just above the discharge bend.

This novel pump head comprises a body 1 having a bent passage 2 therethrough and also provided with a foot 3 and adapted to rest on the margin 4 of the orifice 5 in a support or base 6 and also adapted to receive a pump casing 7, which is fixed as indicated by the threaded joint 8 in the lower end of the bent passage 2. Preferably 70 the joint at 3, 4, between the body 1 and the support 6 is in the nature of a ball-and-socket joint; the foot 3 forming the ball, and the margin 4 forming the socket of the joint; the pivotal support thus formed allows the body 1 to adjust itself on the support 6 by the weight of the depending pump casing 7. Said body 1 is also provided with a shaft bore 9 axially aligned with the orifice 5 and extending through the upper wall 10 of the bent passage 2. Said bore 9 terminates above said wall in a stuffing-box 11 formed on the upper wall 10 and provided with a gland 12. Supporting means which may be in the form of standards 13, 14, are fixed to the body, the same being upper extensions of the upper wall 10 of the body, and at the upper end of said supporting means a bearing support or step 15 is mounted, the same being constructed as a web having a hole 16 therethrough which may be threaded to receive a stand pipe 17.

An annular wall 18 extending up from the web 15 and terminating in a flange 19 105 forms the lower end of the housing and the

bottom of an oil reservoir 20 into which oil may be introduced through an oil supply pipe 21 screwed through said wall 18 at the bottom of the reservoir 20 and extending upward and terminating below the level of the upper end of the stand pipe 17. The housing is continued upward and the oil reservoir is completed by a hollow column 22 provided with an outer flange 23 to rest on flange 19 and an inner depending collar 24 to fit inside the wall 18. Said column is fixed to the body by bolts and nuts 25 in flanges 19 and 23.

A hollow rotor 26 is suitably mounted upon a bearing 27 that is carried by the support 15. A shaft 28 is connected to the rotor by a key and key-way 29 and by a nut 30 screwed down upon a washer 31 on the upper end of a hub 32 of said rotor.

Said rotor is provided at its hub with a flange 33 to which a pulley 34 is fixed, said pulley preferably being provided at its upper end with a head 37 having an orifice 38 of sufficient diameter to pass down over the hub 32, so that the pulley head 37 may rest upon the flange 33 to which said hub is secured by cap screws 39. Lateral thrust bearings 40 and 41 are arranged between the rotor and the inner walls of the hollow housing column 22. Said rotor is fixed to and extends above a foot 42 supported by an anti-friction bearing carried by the bearing support or step 15.

The bearings are common annular bearings and surround the stand-pipe 17 which extends up through the foot 42 and said bearings.

Said anti-friction bearing for the foot 42 is shown as made of the loose annular cup 40 or adjusting washer 43, the race cone 44, anti-friction balls 45 in the race-way of the cone 44, and the upper race-way ring 46 resting on the anti-friction balls 45, said ring 46 being mounted in an annular recess 47 provided therefor in the foot 42.

The hollow column 22 is provided at its upper end with an annular cap 48 that snugly fits around the hub 32 below the flange 33 and that is provided with an annular groove 49 which is cut into the wall of the central orifice of said annular cap 48, so that any splash of oil from below the cap will be intercepted in the channel 49 and returned downward by gravity.

The bearings 40 and 41 are supported by spacers 50 and 51, the lower spacer 50 resting on the upper side of the foot 42 to support the inner race-way 52 of the ball bearing 40 and the upper spacer 51 being a sleeve carried by the annular bearing 40 to support the inner race-way 53 of the upper ball bearing 41.

The oil supply pipe 21 is provided at its upper end with a closure as the screw cap 54. The body 1 is provided with a shoulder 55

to receive clamp means 56 that engage the body and may be adjusted on the base 6 and secured thereto by suitable means as the clamp screws 57.

The shaft 28 may terminate inside the passage 2 and its lower end is provided with a coupling collar 58 fixed thereto by the pin 59 and projecting down below the lower end of the shaft 28 and adapted to receive the upper pump shaft section 60, which may be fastened thereto by the pin 61.

The pump head may be assembled as shown in the drawing as follows: The collar 58 may be fixed to one end of the shaft 28 by the pin 59. The stand-pipe 17 may be screwed into the hole 16, and the shaft 28 be passed through the bore 9, the gland 12, the hole 16 and the stand-pipe 17. The head may then be stood on its lower end, it and the collar 58 resting on a support, not shown, and then the several parts of the lower thrust bearing 27 may be assembled inside the reservoir 20 in an obvious way.

The dust cap and oil retainer 48, the annular bearing 41, spacer 51, annular bearing 40 and spacer 50 will be slipped onto the reduced lower end of the rotor 26. The hollow column 22 is then put into place and the foot 42 is then screwed into place on the rotor. The rotor will then be put in place on the shaft with the foot 42 resting on the lower thrust bearing 27. Then the hollow column 22 may be secured by the bolts and nuts 25, thus completing the reservoir containing and surrounding the stand-pipe and adapted to contain the annular bearings and oil for lubricating the same. The key 29 being applied between the shaft 28 and the rotor, said shaft is adapted to rotate with the rotor. Then the washer 31 and nut 30 may be applied and the nut screwed home, after which the pulley is brought into position on the hub 32 and is fixed to the hub flange 33 by the cap screws 39.

The support 6 is prepared ready to receive the body, but is preferably shipped to the place of use without connecting the body thereto.

At the well or other place of use the base 6 is placed over the well, the casing and shaft 28 with propellers, not shown, are lowered joint by joint into the well in the usual way, and the parts are supported by the elevators, not shown. Then the body and housing with shaft 28 are brought into position to allow the shaft 28 to be connected to the upper shaft section 60.

Then the body and shaft are lowered and the body is brought to the casing and screwed thereon. Then the body is lowered until the ball-like foot 3 rests in the socket or seat 4 therefor.

The gland 12 is always perfectly accessible for tightening the stuffing box to prevent leakage.

- The weight of the depending casing brings the body and the housing and bearings into plumb and the weight of the shaft holds the shaft in true alinement with the 5 casing and thereupon the clamp means 56 may be applied and fixed in place by the clamp screws 57 and the pump is ready to receive the belt, not shown, and put into operation.
- 10 It is understood that any other suitable means to rotate the shaft may be substituted for the pulley without altering other features of the invention and that any form of spout or conduit may be connected to the 15 outlet of the passage 2.

We claim:

1. A base having an orifice therethrough and a body seated in said orifice and forming therewith a ball and socket joint and 20 having a passage therethrough leading from within said orifice to the side of said body, said body also having a bore extending upward from said passage in axial alinement with the orifice to receive a power 25 shaft; a bearing supported by said body above said passage; a rotor supported by said bearing; a shaft connected to said rotor and extending through said bore; means to drive the rotor; a pump casing fixed to 30 said body, said casing communicating with said passage and extending down through said orifice; and a pump shaft connected to said power shaft and extending down through the pump casing, the casing and 35 the pump shaft being free to come automatically to plumb position by force of gravity.
2. A base having an orifice therethrough and a body seated in said orifice and forming therewith a ball and socket joint and 40 having a passage therethrough leading from within said orifice to the side of said body, said body also having a bore extending upward from said passage in axial alinement 45 with the orifice to receive a power shaft; a bearing supported by said body above said passage; a rotor supported by said bearing; a shaft connected to said rotor and extending through said bore; means to drive the 50 rotor; a pump casing fixed to said body, said casing communicating with said passage and extending down through said orifice; a pump shaft connected to said power shaft and extending down through the pump casing; a hollow column fixed to the body; annular lateral thrust bearing between the rotor and the inner wall of the hollow column; a stand-pipe fixed to the body and 55 surrounding the shaft; and means to supply oil to the hollow column, the casing and the pump shaft being free to come automatically to plumb position by force of gravity.
3. A base having an orifice therethrough and a body seated in said orifice and forming therewith a ball and socket joint and 60 having a passage therethrough leading from within said orifice to the side of said body, 65
- said body also having a bore extending upward from said passage in axial alinement with the orifice to receive a power shaft; a bearing supported by said body above said passage; a rotor supported by said bearing; a shaft connected to said rotor and extending through said bore; means to drive the rotor; a pump casing fixed to said body, said casing communicating with said passage and extending down through said orifice; a pump shaft connected to said power shaft and extending down through the pump casing; a hollow column fixed to the body; annular lateral thrust bearing between the rotor and the inner wall of the hollow column; a stand-pipe fixed to the body and surrounding the shaft; and means to supply oil to the hollow column, the casing and the pump shaft being free to come automatically to plumb position by force of gravity.
4. A base having an orifice therethrough and a body seated in said orifice and forming therewith a ball and socket joint and having a passage therethrough leading from within said orifice to the side of said body, 70 said body also having a bore extending upward from said passage in axial alinement with the orifice to receive a power shaft; a bearing supported by said body above said passage; a rotor supported by said bearing; a shaft connected to said rotor and extending through said bore; means to drive the rotor; a pump casing fixed to said body, said casing communicating with said passage and extending down through said orifice; a pump shaft connected to said power shaft and extending down through the pump casing; a hollow column fixed to the body; annular lateral thrust bearing between the rotor and the inner wall of the hollow column; a stand-pipe fixed to the body and surrounding the shaft, the casing and the pump shaft being free to come automatically to plumb position by force of gravity.
5. A body having a bent passage therethrough and a bore extending up through the upper wall of said bent passage and supporting means extending above said bent passage; means supporting said body with a ball and socket joint, the bore being in axial alinement with the ball and socket joint; a pump casing connected to the lower end of said body; a bearing supported on said support; a rotor carried by the bearing; annular lateral thrust bearings carried upon the support and surrounding the rotor; a shaft extending through said bore, support, bearing and rotor and connected to the rotor, and a pulley connected to said rotor and extending downward around the same, the 120 casing and the pump shaft being free to come automatically to plumb position by force of gravity.
6. A pump head comprising a base having an orifice therethrough and a body ad-

- justably seated in said orifice and having a bent passage therethrough; a pump casing extending through said orifice and connected to said body and communicating with said passage, said body being provided with a bore alined with said pump casing and said orifice and also provided with means forming a support; a bearing carried by said support; a rotor 10 supported by the bearing; annular lateral thrust bearings carried upon the support and surrounding the rotor; a shaft extending through said bore, support, bearing and rotor and fixed to said rotor; and a pulley 15 connected to said rotor and surrounding the same, the casing and the pump shaft being free to come automatically to plumb position by force of gravity.
7. The combination in a pump head, of 20 a body having a bent passage therethrough and a bore through the upper wall of said passage; standards extending upwardly from the upper wall of said passage and terminating in a web and an annular wall 25 above said web, there being a bore through the web alined with the bore in said upper wall; an annular anti-friction bearing on said web; a foot supported by said bearing; a stand-pipe screwed into said bore and extending upward from said web; a hollow column fixed to the annular wall and extending above the level of the top of the stand-pipe; a rotor mounted on said foot; annular lateral bearings between said rotor 30 and the inner walls of said column; and a shaft extending through said bores and the stand-pipe and fixed to the rotor and adapted to be rotated.
8. The combination in a pump head of a 35 body having a bent passage therethrough and a bore through the upper wall of said passage; standards extending upwardly from the upper wall of said passage and terminating in a web and an annular wall 40 above said web, there being a bore through the web alined with the bore in said upper wall; an annular anti-friction bearing on said web; a foot supported by said bearing; a stand-pipe screwed into said bore and extending upward from said web and through said foot; a hollow column fixed to the annular wall and extending above the level of the top of the stand-pipe; a rotor mounted on said foot; annular lateral bearings between said rotor and the annular walls of said column; a shaft extending through said bores and the stand-pipe and fixed to the rotor and adapted to be rotated; and an oil pipe communicating with the chamber 55 inside said annular walls and extending upward outside said column to supply oil to the reservoir formed within said annular wall and column.
9. The combination with a web having a bore therethrough; of an annular wall 65 around said bore; a stand-pipe extending up from said bore; a hollow column fixed to the annular wall and extending above the level of the top of the stand-pipe; a shaft 70 extending through said stand-pipe and bore; an annular anti-friction bearing mounted on said web; a foot carried by said anti-friction bearing; a hollow rotor fixed to and extending above said foot; said stand-pipe extending up into said hollow rotor, said rotor being provided with a hub 75 and with a flange extending laterally from said hub; an anti-friction bearing between said rotor and the inside of said column, and a pulley fastened to the flange. 80
10. The combination with a web having a bore therethrough; of an annular wall around said bore; a stand-pipe extending up from said bore; a shaft extending through said stand-pipe and bore; an annular anti-friction bearing mounted on said web; a foot carried by said anti-friction bearing; a hollow rotor mounted on said foot; said stand-pipe extending up into said hollow rotor, said rotor being provided with a hub fastened to said shaft, and with a flange extending laterally from said hub; means fixed to the flange to rotate the rotor, a cover for said annular wall fitting said hub and provided with a channel in 90 the walls of its central orifice; and an anti-friction bearing between said rotor and the inside of said column. 95
11. A pump-head comprising a body provided with a bent passage and with standards extending up from the upper wall of said passage; a ball and socket joint mounting supported by said standards to carry an anti-friction bearing, there being a bore through said upper wall, and said bore 100 terminating in a stuffing-box; a shaft extending through said bore and stuffing-box; a gland on said shaft closing said stuffing-box; and a bearing carrying said shaft and coaxial with the bore and supported by said 105 support, the shaft being free to come automatically to plumb position by force of gravity. 110
12. A pump-head comprising a body provided with a bent passage and with standards extending up from the upper wall of said passage; a ball and socket joint mounting supported by said standards to carry an anti-friction bearing, there being a bore through said upper wall, said bore terminating in a stuffing-box; a shaft extending through said bore and stuffing-box; a gland on said shaft closing said stuffing-box; a bearing carrying said shaft and coaxial with the bore and supported by said support, said support comprising a web having a bore through which said shaft extends, 115 and the shaft being free to come automatic- 120
- 125

cally to plumb position by the force of gravity; a stand-pipe around said shaft and fitted in said bore; means forming with said web an oil reservoir containing said stand-pipe; and means to supply oil to said reservoir.

In testimony whereof we have hereunto

set our hands at Los Angeles, California,
this 22d day of January, 1916.
